UNITED STATES PATENT OFFICE.

FENNER B. BAKER, OF NEW YORK, N. Y., ASSIGNOR, BY DIRECT AND MESNE ASSIGNMENTS, TO ART NEEDLE MANUFACTURING CO., INC., OF NEW YORK, N. Y., A CORPORATION OF NEW YORK.

EMBROIDERING MACHINE.

1,409,903.

Specification of Letters Patent. Patented Mar. 21, 1922.

Application filed April 20, 1920. Serial No. 375,312.

To all whom it may concern:

Be it known that I, FENNER B. BAKER, a citizen of the United States, residing at New York city, in the county of New York and 5 State of New York, have invented a new and useful Embroidering Machine, of which the following is a specification.

My invention relates to a practical and inexpensive device for embroidering or working raised designs in thread upon a fabric.

The invention consists in general of a holder within which there is mounted a reciprocating tubular needle tube, and a special feature of the invention resides in the providing of a tension device which operates as the needle is withdrawn from the fabric on one side of the loop of thread which the needle has just previously carried through the fabric. This renders the loop-forming action of the needle uniform and even. For 10 the purpose of varying the size or formation of the loops thus produced by the needle, the invention contemplates the provision of means for varying the stroke of the needle 15 tube and hence the needle.

The tensioning device is in the form of a tubular thread-engaging element slidably mounted around the needle tube and arranged to clamp the thread or yarn against 20 a lipped shoulder cut from the needle tube. The needle tube is reciprocated by means of this same tubular element or sleeve thus ensuring the application and release of the thread tension in proper time with the movement of the needle.

A special feature of the invention consists in the curved grooved needle. The effect of this formation is to cause the needle to step forward to the extent of the curve each time 25 the fabric is pierced and so produces an automatic and natural feeding action of the device over the fabric.

Other novel features of the invention will appear as the specification proceeds.

The accompanying drawings illustrate in concrete form a practical embodiment of the invention but it will be understood that various changes and modifications may be made without departing from the true scope and 30 spirit of the invention.

Figure 1 is a view in side elevation of the needle tube forming part of an embroidery needle, constructed in accordance with my invention.

Figure 2 is a view in side elevation of the needle tube rotated axially through ninety degrees from the position shown in the first figure.

Figure 3 is a fragmentary view in elevation of the needle end of the stem.

Figure 4 is a view in side elevation of the holder portion.

Figure 5 is a transverse section taken on the line 5—5 of Figure 4.

Figure 6 is a view in end elevation of the holder.

Figure 7 is a view in side elevation of a modified form of holder.

Figure 8 is a similar view of the same part rotated through an angle of ninety degrees from the position shown in the immediate preceding figure.

Figure 9 is an end view of the modified holder.

Figure 10 is a view in elevation of the stop screws employed.

Figure 11 is a view in side elevation of the collar.

Figure 12 is an end view of the collar.

Figure 13 is a view in side elevation of the embroidery needle with parts assembled showing the preferred form of holder, and

Figure 14 is a view in side elevation of the needle assembled and embodying the modified form of holder.

The holder or guard portion of the device is shown as a tubular member Fig. 4 having a foot 12 to bear upon the fabric. The needle tube or stem is shown as a hollow tubular member Figs. 1 and 2 slidably engaged in the holder so as to reciprocate therein. The needle part of this stem can be made detachable as Fig. 3 shows and arranged to slide into the stem or the needle and stem can be constructed as one piece as in Fig. 2. The needle tube is held against turning in the holder by a cut-out 3 of Fig. 2 which engages the screws shown in Fig. 10, which are employed in the series of holes 11 of the guard Fig. 4.

The upward stroke of the needle tube is limited by shoulder 4 of cut-out 3 in Fig. 2 coming in contact with one of the screws shown in Fig. 10 employed in the lower hole 11 in Fig. 4. The downward stroke of the needle tube and hence the active stroke of the needle is governed by the shoulder 5 of cut-out 3 coming in contact

with one of the screws of Fig. 10 employed in one of the top holes at 11 in Fig. 4.

The needle tube is reciprocated by a collar or sleeve shown in Fig. 11. This collar is 5 encompassed around the needle tube between 8 and 7 of Fig. 2. Seven is a shoulder cut from needle tube and establishes a stop for the collar in the downward drive of the needle. Eight is a lip cut from needle tube and 10 forms a stop for the collar in the upward drive of the needle. Eight also is employed in the principles of my tension as I will show in the following explanation:

My tension is established by lip 8, the 15 unique position of the thread hole 6 through which the thread passes and the sleeve of Fig. 11.

The thread passing through the hole 6 (which is immediately under the lip 8) is 20 engaged and clamped by the sleeve when it comes in contact with the lip 8 as the sleeve draws the needle from the fabric thereby applying an intermittent tension to the threads which operates in time with the movement of 25 the needle.

Fig. 2, at 1, shows a grooved curved needle. The effect of this curved grooved needle is to cause the needle to step forward each time the fabric is pierced. The unique construction of this needle as shown in Figs 1 and 3 includes a thread hole 2 which maintains in alignment the thread leading down the groove of the needle to and through the eye. Apparently, the movement of 30 withdrawing the needle from the fabric would step the device backward to a distance equal to the step forward accomplished by a downward stroke of the needle without the accomplishment of any forward travel of the device to secure a stitching operation. But, as a matter of fact and in actual practice the friction between the presser foot of the holder and the fabric is such that the withdrawal of the needle from the fabric while 35 causing a rearward movement of the device does not move the device rearward to a distance equal to the forward movement caused by the insertion of the needle but slightly less, and consequently through repeated reciprocations of the needle there will ensue a 40 resultant forward motion of the entire device combined with slight oscillations of the presser foot on the fabric but slightly greater in its forward motion than in its rearward motion.

The operation of the device, that is the production of the step by step stitching movement is also due partly to the fact that upon the downward movement of the needle 45 it is necessary for the same to pierce the fabric and thus considerable resistance to the side thrust as well as the down thrust of the needle is encountered, which tends to push the whole device forward. On the other hand, as the needle is being withdrawn, the

opening for the needle having already been made, there is not as much resistance offered to the side thrust of the needle and the fabric will give somewhat so as to let the needle spring therefrom when the foot is held comparatively tightly against the fabric. 70

What I claim is:

1. An embroidery needle including a holding means, a fabric engaging means forming part thereof, a member supported by the holding means for reciprocation, a needle forming part of the member, and having a perforation through which a thread may be inserted, said needle being curved so that upon repeated penetrations and withdrawals of the needle into and from a fabric the entire device will be fed along the fabric in a direction facing the concave side of the needle forming a tufted stitch. 80

2. An embroidery needle including a holder, a presser foot formed thereon for support upon the fabric, a member mounted on the holder for reciprocation, a curved needle mounted on the member for movement adjacent the presser foot, said needle having an eye near its point to receive a thread whereby alternate insertions and withdrawals of the needle into and from the fabric will form thread tufts in the fabric and whereby the curvature of the needle combined with frictional engagement of the presser foot on the fabric will result in a forward travel of the device in the direction of the concave side of the needle, and a thread gripping device operable upon withdrawal 90 of the needle to grip the thread. 95

3. An embroidery needle including a tubular holder, a presser foot formed on one end, a stem slidable in the holder, a needle at one end of the stem, means for limiting the amount of movement of the stem, relative to the holder, said needle being curved and perforated and said stem having a perforation, a lip on the stem adjacent the perforation thereof, a sleeve surrounding the stem, and a stop member limiting sliding movement between said sleeve and the lip. 105 110

4. An embroidery needle including a tubular holder, a tubular stem inserted therein for reciprocation, a needle formed on one end of the stem by reducing and cutting away said stem and subsequently forming the needle with a longitudinal groove, said needle being curved and having an eye at its point, means for limiting movement of the 115 stem, a presser foot on the holder, and a thread gripping means on the stem. 120

5. An embroidery needle including a tubular holder, a presser foot thereon, a stem inserted in the holder for reciprocation, one side of the stem being cut away at one point to form a pair of shoulders, a pin passing through the holder forming a stop when engaged by either shoulder to limit movement of the stem, a curved needle at one end of 130

the stem and a thread gripping means at the other end thereof.

6. An embroidery needle including a tubular holder, a tubular stem mounted therein for reciprocation, means for limiting movement of the stem, a perforation at each end of the stem, a lip adjacent one perforation, a needle formed on the stem adjacent the other perforated end whereby a thread may 10 be inserted through the perforation adjacent the lip and after passing through the stem

egressing through the other perforation and through the needle, and a sleeve surrounding the stem to be grasped when the device is operated so that upward movement of the 15 sleeve will grip the thread between the end of the sleeve and the lip.
